DESIGN FOR A COMBINED ADVERTISING

Susan F. Williams, New York, N. Y.

Application April 25, 1934, Serial No. 51,505

Term of patent 3½ years

To all whom it may concern:

Be it known that I, SUSAN F. WILLIAMS, a citizen of the United States, residing in New York, county and State of New York, have invented a new, original, and ornamental Design for a Combined Advertising Figure and Support Therefor, of which the following is a specification, reference being had to the accompanying drawing, forming part thereof.

Fig. 1 is a side elevation of the combined advertising figure and support therefor;

Fig. 2 is a front elevation of the same.

I claim:

The ornamental design for a combined advertising figure and support therefor, as shown.

SUSAN F. WILLIAMS.
